UNITED STATES PATENT OFFICE

WALLACE H. GRANGER, OF SAN FRANCISCO, CALIFORNIA

INKING SYSTEM FOR PRINTING PRESSES

Application filed July 16, 1929. Serial No. 378,775.

My invention relates to improvements in inking systems for printing presses, and it consists in the combinations, constructions and arrangements hereinafter described and 5 claimed.

In the standard newspaper printing press, it is customary to have the inking mechanism operated directly from the press and to deliver substantially the same quantity of ink 10 whether the press is running at a slow speed or at its maximum speed.

The principal object of my invention is to provide an inking mechanism in which ink is fed to the ink-distributing drum under a 15 pressure which is built up by an ink pump that is driven by an independent electric motor. The quantity of ink fed to the ink-distributing drum is automatically controlled by a pressure-reducing valve that in 20 turn is actuated by a motor which is connected in parallel with a similar motor that is used for actuating a rheostat. The rheostat is placed in the main line circuit of the press and controls its speed. The pressure- 25 reducing valve automatically opens when the press increases its speed, and automatically lessens the supply of ink as the press decreases its speed.

A further object of my invention is to provide a device of the type described in which novel means is used for instantly cutting off the flow of ink to the ink-distributing drum as soon as the printing press is brought to a stop. The ink is delivered to the drum in a 35 pulsating stream controlled by a needle valve. This pulsation of the flow of ink permits the needle valve to be opened more widely than would be possible with a steady and uniform flow of ink. The needle valve will not clog 40 as quickly when opened wider.

Other objects and advantages will appear as the specification proceeds, and the novel features will be particularly pointed out in the claims.

My invention is illustrated in the accompanying drawings, in which

Figure 1 is a schematic showing of the device;

Figure 2 is an enlarged sectional view of 50 the ink fountain; and

Figure 3 is a side elevation of the ink fountain.

In carrying out my invention, I provide an ink-containing tank 1 that has a supply pipe 2 leading to an ink pump 3 and an overflow 55 pipe 4 leading from the pump back to the tank.

A motor 5 actuates the pump 3 and sends ink under pressure through a pipe 6 and into a pressure tank 7. A check valve 8 is disposed in the pipe 6 and determines the pressure of the ink within the tank 7. It should be noted that the ink is filtered as it passes through the pipe 2, and for that purpose I show a standard filter 9 placed in this pipe. 65

The ink passes from the pressure tank 7 through a second filter 10, similar to the filter 9, and then past a pressure-reducing valve 11. This valve is opened and closed by means of a motor 12 that is operatively connected 70 to the valve 11 by gearing 13.

The purpose of the valve 11 is to control the quantity of ink delivered to an ink-distributing drum 14. When the printing press is operating at maximum speed, the valve 11 will be wide open. The valve is partially closed when the printing press slows down. In this way the required amount of ink is delivered to the ink-distributing drum regardless of the speed of the press. The type 75 of valve shown in the drawings is a Mason No. 33 reducing valve. It is obvious that another type of reducing valve can be used without departing from the spirit and scope of the invention.

It is best to show how the valve 11 is automatically opened or closed as the printing press changes its speed from either fast to slow or vice versa. I have shown wires 15 leading from a rheostat 16 to the printing press, variable speed motor 15' which in turn is connected to the printing press by any suitable drive, such as a chain drive 16'. A switch arm 18 is provided in the rheostat, and this arm is swung by means of a worm 19 that is rotated by a motor 20. The motor 20 is similar to the motor 12, and is connected in parallel therewith. A reversing switch indicated at 21 is used for rotating both motors 12 and 20 in one direction or the other. 95 100

The rotation of these motors in one direction will move the switch arm 18 over the rheostat 16 for causing the printing press to gradually increase in speed, and will also cause the valve 11 to gradually open for delivering a larger quantity of ink to the printing press. The reversing of the motors 12 and 20 will automatically cut down the speed of the press and will reduce the amount of opening in the valve 11 for causing it to deliver a smaller amount of ink. In this way the amount of ink is automatically controlled with the speed of the printing press.

The ink passes from the valve 11 to a magnetically-controlled valve 22. The particular type of valve shown in the drawings is called a solenoid-operated regulator Mason No. 257. It is obvious that other types of magnetic valves can be used. The solenoid 23 of the valve is connected by wires 24 to the wires 15. A current passing through the wires 15 will also pass through the wires 24 and will open the valve 22. As soon as the current is shut off to the printing press, the solenoid 23 will become de-energized and the valve 22 will immediately close, cutting off any further flow of ink to the printing press. The valve 11 will thereafter gradually close. The starting of the press again into operation will instantly open the valve 22. The opening of the valve 11 is regulated by the speed of the press in the manner already described.

The ink flows from the valve 22 through a pipe 25 to branch pipes 26 that communicate with chambers 27 in an ink container 28. A gate valve 29 is disposed in the pipe 25 and control valves 30 are disposed in the branch pipes 26. Referring to Figure 2, it will be noted that the ink flows from the ink container 28 up through a rocker valve 31 past a needle valve 32 and on into an ink ejector 33. There is an ejector 33 for each column of printing on the newspaper. The rocker valve 31 controls all of the ink ejectors 33. There is a separate needle valve 32 for each ink ejector.

The chambers 27 in the ink container 28 are formed by movable dividing walls 34. The length of each chamber is equivalent to a sheet of paper one newspaper page in width. It is possible to cut off any one of the chambers from the pipe 25 by means of the valves 30. All of the chambers may be cut off by the gate valve 29.

The purpose of the rocker valve 31 is to cause ink to pulsate through the ink ejector 33. I have found that the pulsation of the ink through the ink ejector will permit the needle valve 32 to be opened wider than when a continuous stream of a uniform quantity of ink is forced through the ejector. The wider opening of the valve 32 does away with the clogging of the ink in the valve.

The rocker valve 31 is actuated by an arm

35 (see Figures 1 and 2). This arm is connected by a link 36 to an eccentric 37 which in turn is geared to the ink-distributing drum 14 as shown. Any other suitable mechanism for rocking the arm 35 can be used.

From the foregoing description of the various parts of the device, the operation thereof may be readily understood.

The operator starts the printing press 75 functioning by closing the switch 21 and keeping the switch closed until the rheostat switch arm 18 is moved to the desired point. Standard presses have different push buttons for slow and fast, but this structure 80 forms no part of my invention, and I have therefore not shown such push buttons. The valve 11 opens with the movement of the switch arm 18 and closes when the switch arm moves back to neutral position. The 85 motor 5 is started and will deliver ink from the tank 1 to the pressure tank 7 and keep the ink within the tank 7 at a predetermined pressure. This ink under pressure is delivered to the ink-distributing drum 14 and 90 associate ink rollers 17 in varying quantities depending upon the speed of the printing press. As many ink chambers as desired may be turned on or off. A stopping of the 95 printing press will close the valve 22, and the device is ready for the next operation.

Although I have shown and described one embodiment of my invention, it is to be understood that the same is susceptible of various changes, and I reserve the right to employ such changes as may come within the scope of the invention as claimed.

I claim:

1. In combination with a printing press, an electrical circuit for actuating the same, 105 a rheostat for controlling the circuit, a second electrical circuit for actuating the rheostat, an ink-feeding mechanism for the printing press, a valve controlling the ink-feeding mechanism, and a motor for operating 110 the valve and having its circuit shunted into the second circuit for opening the valve simultaneously with the closing of the rheostat, the opening of the valve varying in direct proportion to the length of time the secondary circuit remains closed.

2. In combination with a printing press, an electrical circuit for actuating the same, means associated with the circuit for controlling the amount of current flowing in the circuit and the resultant speed of the printing press, an ink-feeding mechanism for the printing press, and means for controlling the latter associated with the speed control means for effecting a common control for the speed of the printing press and the ink feed.

3. In combination with a printing press, an ink-feeding mechanism, an electrical circuit for actuating the printing press, a valve 120

for the ink-feeding mechanism and an electrical circuit for operating the valve associated with the first circuit for instantly closing the valve when the circuit to the press is broken.

4. In combination with an electrically driven printing press, an ink-feeding mechanism having its outlet at the very top, and an electrically operated means associated with the latter for automatically discontinuing the flow of ink when the electric circuit controlling the press is broken.

5. An ink-feeding mechanism for an electrically driven printing press comprising a tank, means for maintaining ink therein under pressure, an ink delivery device, having its outlet at the very top, a conduit connecting the latter with the tank, a valve in said conduit, and electrical means connected with the printing press circuit for operating the valve whereby the flow of ink is controlled and immediately stopped when the circuit controlling the press is broken.

6. An ink-feeding mechanism for a printing press comprising a tank, means for maintaining ink therein under pressure, an ink delivery device, a conduit connecting the latter with the tank, a valve in said conduit, and reversible electrical means for operating the valve whereby the flow of ink is controlled.

7. An ink-feeding mechanism for a printing press comprising a tank, an ink delivery device, having its outlet at the very top, controlled means for feeding ink from the tank to the delivery device, and means for maintaining ink in the tank under pressure comprising a main supply vessel, a conduit connecting the latter with the tank, a pump in said conduit, and an overflow pipe connected with the conduit.

8. An ink-feeding mechanism for a printing press comprising a tank, an ink delivery device, having its outlet at the very top, controlled means for feeding ink from the tank to the delivery device and means for maintaining ink in the tank under pressure comprising a main supply vessel, a conduit connecting the latter with the tank, a pump in said conduit, and an overflow pipe connected with the conduit leading back to the main supply vessel.

9. In combination with a printing press, an ink delivery device, having its outlet at the very top, means for feeding ink thereto under pressure an oscillating valve for the latter means, and means for oscillating the valve when the press is active.

10. An inking system for printing presses comprising a circuit for a printing press, a rheostat for controlling the circuit, a reversible motor operatively connected to the rheostat, an inking system including a conduit, a valve disposed in the conduit and designed to be gradually opened and closed, a second reversible motor operatively connected

to the valve, and a circuit electrically connecting the two motors, whereby the flow of ink will be varied in direct proportion to the speed of the press.

11. An inking system for printing presses comprising a circuit for a printing press, a rheostat for controlling the circuit, a reversible motor operatively connected to the rheostat, an inking system including a conduit, a valve disposed in the conduit and designed to be gradually opened and closed, a second reversible motor operatively connected to the valve, a circuit electrically connecting the two motors, whereby the flow of ink will be varied in direct proportion to the speed of the press, a second valve disposed in said conduit, electric means for holding said second valve open so long as the electric means is energized, said electric means being electrically connected to the printing press circuit, said second valve immediately closing when the circuit to the printing press is broken.

12. An inking system for printing presses comprising a circuit for a printing press, a rheostat for controlling the circuit, a reversible motor operatively connected to the rheostat, an inking system including a conduit, a valve disposed in the conduit and designed to be gradually opened and closed, a second reversible motor operatively connected to the valve, a circuit electrically connecting the two motors, whereby the flow of ink will be varied in direct proportion to the speed of the press, and a reversing switch for the second circuit.

13. In an inking system for a printing press, an elongated ink container of substantially the same length as the ink drum of the press, partitions dividing said container into compartments, means for pumping ink up to the container, the container being disposed above the pumping means, valves for controlling the ink entering each compartment, a plurality of nozzles leading from the top of each compartment, and a control valve for each nozzle.
